UNITED STATES PATENT OFFICE.

ALBERT STONE, OF CLARKSVILLE, MISSOURI.

MOLDBOARD.

Application filed November 2, 1923. Serial No. 672,418.

To all whom it may concern:

Be it known that I, ALBERT STONE, a citizen of the United States, residing at Clarksville, in the county of Pike and State of Missouri, have invented new and useful Improvements in Moldboards, of which the following is a specification.

The object of this invention is the provision of a rotary mold board for plows.

10 A further object is to cut away the upper corner of a mold board to produce a rounded depression therein the outer wall being bevelled inwardly and the depression being covered by a disk which is supported for 15 free rotation on the mold board, and whereby by the dirt elevated by the plow will be directed against the disk to cause the rotation of the latter and to force the dirt to one side of the plow with the least amount of friction, so that the draft strain upon the plow 20 is greatly reduced.

The drawings which accompany and which form part of this application illustrate a satisfactory embodiment of the invention, 25 and wherein:

Figure 1 is a side elevation of a mold board embodying the improvement.

Figure 2 is a rear elevation thereof.

30 Figure 3 is a sectional view on the line 3—3 of Figure 1.

In the drawings the numeral 1 designates the mold board of an ordinary construction of plows. The upper outwardly rounded rear corner of the mold board is in the present instance notched or cut away to provide a lower angle edge 2, which merges into an inwardly rounded edge 3. The edges 2 and 3 provided by the cut away portion of the

mold board are bevelled to provide inner sharpened surfaces.

Secured on the rear face of the mold board 40 1 by means 4 there is a bracket 5 offset to provide an extending arm 6, which is disposed centrally in the notched or cut away portion of the said mold board. On the 45 arm 6 of the bracket there is pivoted as at 7 a disk cutter 8. The cutter fully covers the notched portion of the mold board and extends outwardly therefrom. The disk is so arranged that dirt elevated by the plow will 50 contact therewith and by virtue of such contact will cause the rotation thereof so that the least amount of friction between the dirt and the mold board will be thus afforded and consequently the draft power of the 55 plow usually necessitated will be materially decreased.

The beveled edge of the notched portion of the mold board directs the dirt against the disk and also serves as a scraper for said 60 disk.

Having described my invention, I claim:

In a plow construction, a mold board having its upper rear corner notched to provide a lower angle edge which merges into an upwardly directed inwardly rounded edge, both of said edges being sharpened, an angle bracket secured to the rear face of the mold board and projecting into the 65 notch, and a disk cutter pivotally secured to the bracket, and covering the notch of the mold board, as and for the purpose set forth.

In testimony whereof I affix my signature.

ALBERT STONE.
